[57] CLAIM

We claim the ornamental design for tire, as shown and
described.

DESCRIPTION

FIG. 1 is a perspective view showing a tire of our new
design;FIG. 2 is a front view, which is the same as the rear view, of
FIG. 1;

FIG. 3 is a partial enlarged view of FIG. 1;

FIG. 4 is a sectional view of FIG. 1; and,

FIG. 5 is a right side view which is the same as a left side
view of FIG. 1.In the drawings, the dark stippled surface shading represents
the recessed portion of the tread grooves, having a depth as
best shown in FIG. 4.
